UNITED STATES PATENT OFFICE.

CLYDE T. MULVANY, OF PUEBLO, COLORADO, ASSIGNOR OF ONE-TENTH TO RUFUS LOWRANCE, AND OF ONE-TENTH TO ELMER CLATFELTER, BOTH OF PUEBLO COUNTY, COLORADO, TWO PER CENT TO LORENA MAY BELIAN, OF KIMBALL COUNTY, NEBRASKA, ONE-TWENTIETH TO PAUL JONES, OF PUEBLO COUNTY, COLORADO, AND ONE-TENTH TO MARKUS H. BELIAN, OF LARIMER COUNTY, COLORADO.

BOLT-HEATING FURNACE.

Application filed February 9, 1924. Serial No. 691,639.

To all whom it may concern:

Be it known that I, CLYDE T. MULVANY, a citizen of the United States, residing at Pueblo, in the county of Pueblo and State 5 of Colorado, have invented certain new and useful Improvements in Bolt-Heating Furnaces, of which the following is a specification.

This invention relates to a bolt heating 10 furnace and has for its particular object to improve, simplify and render more efficient, devices of this character.

The invention is further distinguished by its universality, particularly in view of the 15 fact that it is capable of heating with equal efficiency, stock of short or long lengths.

The invention also consists in the novel combination, construction and arrangement of parts, all of which will be made 20 more apparent hereinafter, as this description proceeds, especially when considered in connection with the accompanying drawings wherein;

Figure 1 is a side elevation, partly in section, of a bolt heating furnace constructed 25 in accordance with my invention;

Fig. 2 is a transverse sectional view, taken substantially on the plane indicated by the line 2—2 in Fig. 1;

Fig. 3 is a top plan view of the furnace, with certain parts broken away to show interior construction;

Fig. 4 is an end view, as seen from the right of Fig. 1; and,

Fig. 5 is an end elevation of the opposite end of the furnace.

Referring now particularly to the drawings wherein like reference characters indicate like parts, it will be noted that the 40 reference character 10 indicates the furnace in its entirety, which includes a top 11, preferably slightly arched, and from which extends a flue or chimney 12. The reference characters 13 and 14 indicate respectively the front and rear ends of the furnace, the flue or chimney being preferably arranged near the rear end, as clearly illustrated in Fig. 1, and adjacent the front end thereof there is arranged a fuel nozzle 15, connected to a fuel supply pipe 16, provided with a valve 17. The fuel supply

produces a hydro-carbon jet which impinges against a baffle wall 18 arranged in the fire box 19 of the furnace. By reason of this contact with the baffle wall 18, the 55 flame is broadened and spread throughout the fire box, for a purpose which will appear more apparent hereinafter.

Arranged adjacent the rear end 14 of the furnace is a hopper 20 into which the 60 stock to be heated is placed, the opening at the bottom of the hopper communicating with an opening 21, formed in the rear wall of the furnace.

However, the passage of the stock from 65 the hopper 20 into the furnace is controlled by sprocket wheels 22 secured on a shaft 23, extending transversely at the rear of the furnace. This shaft may be supported by a suitable bracket 24. The notches on 70 the sprocket wheel 22 are of a size sufficient to engage the rods 25 which constitute the stock to be headed.

The fire box 19 of the furnace is relatively narrow, as clearly shown in Fig. 2, and the side wall on one side of this fire box is formed with a longitudinally extending opening 26, and provided at the bottom with a water jacket 27. The longitudinal opening 26 permits the stock 25 to pass longitudinally of the furnace, the movement of the stock being insured by inclining the opening 26 downwardly from the rear wall of the furnace toward the front thereof, as clearly illustrated in Fig. 1. Obviously, 80 the water jacket prevents the over-heating of that portion of the stock arranged within the furnace wall.

In the passage of the stock from the rear of the furnace to the front, the end thereof 90 25', which is the end to be headed, is subjected directly to the heat of the hydro-carbon jet, so that after its passage through the furnace, it is in a condition to be passed to the heading machine.

Arranged adjacent the front end 13 of the furnace is a second shaft 28, which may be supported in suitable brackets 29. This shaft is provided with one fixed sprocket wheel 30 and sprocket wheel 31 formed 100 with a collar 32, provided with a set screw 33 whereby this sprocket wheel may be

fixed in any of its adjusted positions on the shaft 28. The sprocket wheels 30 and 31 are arranged adjacent the outlet end 34 of the passageway through which the stock to be headed passes. These forwardly arranged sprocket wheels are provided so that the delivery of the stock from the furnace may be controlled.

For rotating the sprocket wheels 30—31 at 10 will, there is provided a foot controlled arrangement consisting essentially of a shaft 35 arranged preferably parallel with the shaft 28 and adjacent the base of the furnace. This shaft has rotatably mounted 15 thereon a foot pedal consisting of treadles 36 and 37, the treadle 37 being pivoted directly on the shaft 35, while the treadle 36 is pivoted as at 38 on the treadle 37. A spring 39 arranged between the two treadles 20 tends to maintain treadle 36 spaced from treadle 37, as illustrated in Fig. 1.

Connected to treadle 36 is a latch bar 40, the upper end of which engages in the notches of the ratchet 31. Pivoted to the 25 treadle 37, as at 41, is a pawl 42, which is preferably connected by means of a coil spring 43 to the guiding frame of the latch bar 40.

Obviously, when the pedal consisting of 30 the treadle members 36—37 is first depressed, the treadle member 36 will move toward the treadle 37 and release the latch bar 40 from engagement with the sprocket wheel 31. A continued pressure upon the pedal will rock 35 the same about the shaft 35, whereupon the pawl 42 will be pushed upwardly, rotating the sprocket wheel one notch to cause one of the pieces of stock to be discharged. When 40 the foot of the operator is removed from the pedal, the parts will, by reason of the springs associated therewith, return to the position illustrated in Fig. 1.

Arranged adjacent the discharge end of 45 the furnace is a pan 44, into which stock discharged from the furnace is deposited, and from which it is taken and carried to the heading machine.

The shafts 23 and 28 are extended out 50 slightly beyond one side of the furnace, and are each provided with a sprocket wheel 45, adapted to be engaged by a sprocket chain 46. Thus, when the sprocket wheel 31, and consequently the shaft 28 are rotated, this rotation will be transmitted by means of the 55 sprocket wheels 45 and chain 46 to the shaft 23, arranged adjacent the rear of the furnace, whereupon this shaft, as well as the sprocket wheels 22 will partake simultaneously of a rotation to a similar degree, so 60 that stock will be fed from the hopper 20 onto the inclined runway simultaneously and in a like amount, as it is delivered from the furnace into the pan 44, at the front thereof.

By adjusting the sprocket wheel 31 on the 65 shaft 28 and by adjusting the corresponding

sprocket wheel 22 at the rear of the machine on the shaft 23, stock of considerable length may be handled as efficiently as stock of short length, thus materially increasing the effectiveness and universality of the furnace.

Obviously, as the stock rolls down the inclined runway with the end thereof constantly subjected to the heat of the furnace, the end will be heated to a red heat, whereupon 70 at its discharge, it may be taken to the heading machine and headed in the customary manner. Obviously, by reason of the structure herein described, the machine is capable of operation by a single person arranged at the discharge end of the furnace.

While the invention has been described herein in some detail, it is not intended that the same be limited to the above disclosure, but reservation is made to make such changes in the details of construction and combination and arrangements of parts as may come 80 within the purview of the accompanying claims.

Having thus described my invention what I claim is:

1. In a bolt heating furnace, a hopper for the surplus stock, an inclined runway in the wall of the furnace communicating with the fire box along which said stock is adapted to pass, and means including simultaneously 95 rotatable shafts with sprockets arranged adjacent said hopper and adjacent the discharge end of said runway for controlling the passage of the stock into said runway and of the discharge of said stock from said furnace, at least one of the sprockets associated with each of said shafts being adjustably mounted thereon for the purpose described.

2. In a bolt heating furnace, a fire box, a baffle in said fire box for spreading the flame throughout the same, one side wall of said furnace being formed with an inclined passageway, a water jacket arranged in the furnace wall at the lower side of said passageway, a hopper arranged adjacent one end of said furnace for receiving the supply of stock to be heated, said hopper communicating with one end of said passageway, shafts arranged adjacent each end of said furnace, means connecting said shafts for simultaneous rotation, sprocket wheels arranged on said shafts, the sprocket wheels on the shaft adjacent said hopper controlling the passage of the stock from said hopper into said passageway, the sprocket wheels on the other of said shafts controlling the discharge of said stock from the discharge end of said passageway and means for rotating said sprocket wheels.

3. In a bolt heating furnace, a fire box, a baffle in said fire box for spreading the flame throughout the same, one side wall of said furnace being formed with an inclined passageway, a water jacket arranged in the furnace wall at the lower side of said passageway,

way, a hopper arranged adjacent one end of said furnace for receiving the supply of stock to be heated, said hopper communicating with one end of said passageway, shafts 5 arranged adjacent each end of said furnace, means connecting said shafts for simultaneous rotation, sprocket wheels arranged on said shafts, the sprocket wheels on the shaft adjacent said hopper controlling the passage 10 of the stock from said hopper into said passageway, the sprocket wheels on the other of said shafts controlling the discharge of said

stock from the discharge end of said passageway and means for rotating said sprocket wheels consisting of manually controlled 15 pedals, a latch bar operatively connected to one of said pedals and disengageable upon the depression of the same and a pawl connected to the other of said pedals and operable upon the depression of the same for engaging one of said sprocket wheels to rotate the same tooth space.

In testimony whereof I affix my signature.
CLYDE T. MULVANY.
